MAGAZINE RACK

John Volpi, Aurora, Colo., assignor to Aurora Ornamental Iron, Aurora, Colo., a partnership

Application February 27, 1958, Serial No. 49,827

Term of patent 14 years

(Cl. D33—3)

Fig. 1 is a front perspective view of a magazine rack, showing my design;

Fig. 2 is a side elevational view of the magazine rack; and

Fig. 3 is a front elevational view thereof.

I claim:

The ornamental design for a magazine rack, as shown.
